UNITED STATES PATENT OFFICE.

ALBERT D. ELSTER, OF MERIDEN, CONNECTICUT.

GASOLENE-WATER SEPARATOR.

1,216,219.

Specification of Letters Patent. Patented Feb. 13, 1917.

Application filed August 26, 1915. Serial No. 47,525.

To all whom it may concern:

Be it known that I, ALBERT D. ELSTER, a citizen of the United States, residing at Meriden, in the county of New Haven and State of Connecticut, have invented certain new and useful Improvements in Gasolene-Water Separators, of which the following is a specification.

My invention relates to improvements in gasolene-water separators, and the object of my improvement is to produce a device suitable for use in the line of supply for internal combustion engines on automobiles, motor cycles, and motor boats using gasolene for separating water from the gasolene and with which I find it convenient to incorporate a strainer in most cases, and applies in part to certain features divided out from my application which issued as Patent No. 1,093,258, April 14, 1914, and to certain improvements therein.

In the accompanying drawing,

Figure 1 is a side elevation of my improved gasolene-water separator.

Fig. 2 is a plan view of the same.

Fig. 3 is a sectional view on the line $\alpha-\alpha$ of Fig. 2.

Fig. 4 is a similar view of a modification of my gasolene-water separator.

My improved gasolene-water separator consists of a structure in globular form composed of an upper member 10 and a lower member 11 that meet along a horizontal plane, held together by an axial screw 13.

The meeting edges of the members 10 and 11 are formed suitably to make a close fitting joint, as shown at 12 and the lower member 11 is provided with an inlet connection 14 for gasolene and the upper member 10 with an outlet connection 15, and the lower member 11 is provided at the lower end with a purging cock 16 in the form of a petcock.

Within the globular structure described is housed a piece 17 of straining or filtering material, which as shown is of wire gauze and is positioned adjacent the junction 12 of the upper and lower members 10 and 11.

The axial screw 13 extends through a hole 21 in the upper member 10; has the lower threaded end engaged with a threaded hole 18 in a boss 19 extending upwardly from the lower wall of the lower member 11; has the head 20 at the upper end; and engages by the said head 20 with packing material 22 interposed between the same and the seat 23

provided therefor in the opposed upper wall portion of the upper member 10.

A guide sleeve 24 is secured by its upper end in the upper wall of the upper member 10 and extends downwardly axially in alignment with the hole 21, passing through the strainer material 17 and is a fit for the body portion of the screw 13.

The internal boss 19 connects by means of an axial hole or bore 25 in continuation 65 of the hole 18 with the pet-cock 16 and is provided with a plurality of radial holes 26 which connect the hole or bore 25 with the interior of the structure, and which are positioned at the lowest point possible so as to 70 permit of drawing all the water therefrom through the pet-cock 16 during the flushing operation.

In use, the upper and lower members 10 and 11 are brought together with the edges 75 joined as shown at 12, and with the strainer material 17 bridging the space across the structure, the members 10 and 11 being turned relatively the one to the other to get the proper angular relation of the inlet 14 80 and outlet 15, as desired and then the screw 13 with the packing washer 22 mounted thereon is inserted through the hole 21 and tubing 24, and the threaded lower end is engaged with the threaded hole 18 in the boss 85 19, and the screw 13 is tightened suitably to secure the members 10 and 11 together and in a manner to prevent leakage of gasoline from the joint 12 or at the head 20.

After being in use for a short time as an 90 ordinary strainer there will be an accumulation of water, which will collect in the lower portion of the lower member 11, around the boss 19. The removal of this water is facilitated in the device shown by 95 the manipulation of the pet-cock 16. Such removal of the water from the gasoline is one of the principal functions of my device as shown and described.

It will be noted that as shown in Fig. 3 100 the boss 19 and the body portion of the pet-cock 16 are integral with the body wall of the lower member 11.

This method of construction involves certain difficulties in manufacture due to the 105 radial position of the drainage passages 26 and particularly to the fact that so much importance attaches to having the same positioned so low down in the structure, as described, and I overcome this difficulty and 110

make certain other changes of importance in the modification shown in Fig. 4, as explained herewith

In the first place, the seat 23^a for the packing washer 22^a is flat instead of conical as in the seat 23 and the said packing-washer 22^a is annular in form, and flat, as an ordinary washer.

The filtering or straining material consists of two layers, the upper 17^a of wire gauze and the lower 17^b of felt or fabric, and these are housed in the upper member 10^a and are fixedly maintained in position by a pair of spring positioning rings 17^c, one on the upper side and one on the lower side and which are seated in grooves 17^d in the side wall of the said upper member 10^a.

I furthermore provide an annular seat 17^e on the guide tube 24^a in the form of an outwardly extending shoulder that serves as a seat for the inner or middle portion of the composite filtering material 17^a and 17^b and I form this shoulder by up-setting the material of the tube 24^a, as shown.

The joint 12^a between the upper and lower members 10^a and 11^a differs from the joint 12 for the members 10 and 11 in that the opposed edges are finished square and annular, and a packing washer 12^b of lead is interposed between them, and one of the members, as shown, the lower member 11^a, is provided with an exterior inclosing lip 12^c.

The guide tube 24^a is made appreciably longer than the guide tube 24 and extends appreciably below the filtering layers and the joint 12^a, and well into the body portion of the lower member 11^a as shown, suitably to serve as an effective guide for the screw 13^a so as to direct the same to the screw threaded hole 18^a in the boss 19^a as well as to guide the same past the said filtering layers 17^a and 17^b.

The pet-cock 16^a is made a separate piece from the lower member 11^a; the upper portion thereof 19^b is in the form of a neck, which is connected to the said lower member 11^a by a screw threaded connection 19^c; the boss 19^a is an upward extension of the said neck 19^b, the screw threaded hole 18^a in the boss 19^a is a continuation of the bore 27 of the pet-cock 16^a; and the radial openings or passage ways 26^a are positioned in the lower portion of the boss 19^a so that the lower portion thereof is flush with the lower inner wall of the lower member 11^a.

The outlet 15^a is positioned in the side wall of the member 10^a and the inlet 14^a is positioned in the side wall of the lower member 11^a.

It will be noted that the position of the junction 12^a of the upper and lower members 10^a and 11^a is relatively high, so that the lower member 11^a is appreciably deeper and longer than the upper member 10^a and

that the position of the inlet connection 14^a is relatively elevated, or close to the junction 12^a and remote from the bottom wall, and the purpose of this is that the lower member 11^a may have capacity to serve as a reservoir to hold an appreciable quantity of water and without interfering with the flow in proper manner of the relatively pure and unmixed gasoline or other liquid fuel.

That is to say, as shown and described, the upper and lower members 10^a and 11^a are so positioned and designed that the lower member 11^a is suitable to serve as a reservoir for the purpose mentioned and the upper member 10^a is suitable to serve as a cover therefor, provides a means for connecting the outlet 15^a, and serves as a housing for the filtering washers 17^a and 17^b, so that the same may be removed as a unit with the said upper member 10^a.

In the style shown in Fig. 3 the boss 19 is integral with the lower member 11 and in the style shown in Fig. 4 the boss 19^a is integral with the pet-cock 16^a, and in both styles the boss 19 or 19^a as the case may be serves as an upwardly projecting member that extends upwardly from the bottom of the lower member 11 or 11^a.

It is understood that different kinds of filtering material can be used as desired, such as felt, or chamois, or any other material that can readily be held in place and will permit the free passage of gasoline and prevent the passage of solid foreign particles, such as dirt or grit.

The feature of permitting of adjustment of the inlet and outlet at any angle relatively one to the other is a particular convenience, the joint connecting the two parts of the casing being such as to permit of setting these at any position desired. One of the alternative positions is shown in broken lines in Fig. 2.

I claim as my invention:

1. A gasoline-water separator comprising a structure of globular form and composed of two members having edges in abutment, one of the said members having an inlet connection and the other an outlet connection, a purging cock connected to the lower of the said members, a boss in the form of an upwardly projecting member that extends upwardly from the lower inner wall of the said lower member having radial holes flush with the said wall and connecting with the said cock, and having a threaded hole in the upper end, a screw extending through the upper wall of the said upper member and engaged with the said screw threaded hole, and packing material positioned between the head of the said screw and the said upper wall.

2. In a gasoline-water separator comprising a globular structure composed of two members held together by an axial screw,

one of the said members having an inlet connection and the other an outlet connection, the said screw passing through the upper of the said members, being engaged by a screw threaded neck on the upper end engaged with the said lower member, and the 10 said boss being in the form of an upward extension of the said neck.

5 the head portion with the said upper member, and being engaged by the threaded lower end with a boss positioned internally in the said lower member, a pet-cock having
